(57) **CLAIM**

I claim the ornamental design for a mailbox sign, as shown and described.

DESCRIPTION

FIG. 1 is a front perspective view of a signage design of the present invention;

FIG. 2 is a front elevational view of the signage design of FIG. 1;

FIG. 3 is a rear elevational view of the signage design of FIG. 1;

FIG. 4 is a side elevational view of the signage design of FIG. 1;

FIG. 5 is a top plan view of the signage design of FIG. 1;

FIG. 6 is a bottom plan view of the signage design of FIG. 1;

FIG. 7 is a front perspective view of an alternative signage design of the invention;

FIG. 8 is a front elevational view of the signage design of FIG. 7.

FIG. 9 is a rear elevational view of the signage design of FIG. 7

FIG. 10 is a side elevational view of the signage design of FIG. 7.

FIG. 11 is a top plan view of the signage design of FIG. 7; and,

FIG. 12 is a bottom plan view of the signage design of FIG. 7.

The broken lines depicting a printed message shown in FIGS. 1, 2, 7, and 8 are for illustrative purposes only and form no part of the claimed design.
